ACCELERATED AGING OF DISTILLED LIQUORS

Wilbur A. Carrell, Pittsburgh, Pa.

Application May 5, 1934, Serial No. 724,053

2 Claims. (Cl. 202—78)

My invention relates to whisky, rum, brandy, and other alcoholic distillates or liquors which are intended for drinking, and more particularly the invention consists in a method of quickly aging such liquors.

It will be understood that liquor coming from the still contains butyl alcohol, amyl alcohol, and other oils or alcohols in such state that the liquor is unfit for drinking. Hence, the liquor must be rectified or "aged" before it is fit for consumption. The so-called aging, or the rectifying of the liquor is essentially a chemical process in which the more harmful and distasteful ingredients of the green liquor are cured, or are converted into substances which give the desired flavor and bouquet to the liquor. The chemistry involved is complicated, and the chemists are not in accord as to what the various reactions are. A detailed consideration of the chemical reactions is not essential, to enable one skilled in the art to practice my invention, and, accordingly, I shall so far as practical avoid chemical theory.

It has been known hitherto that the "aging" process may be accelerated by heating the liquor in the presence of charcoal, but, so far as I am aware, no one has provided an application of this knowledge which is practical under the conditions of present day manufacture. The Government has established a definite procedure which all licensed persons must follow in the manufacture of liquor. The purpose of the governmental regulation and supervision is primarily to insure equal and uniform taxation, and to safeguard the public against inferior products. For manifest reasons, any "aging" process which does not lend itself to the established regulations will not be tolerated. Furthermore, the attending dangers of fire and explosion have prevented the use of most quick "aging" methods which have been proposed hitherto.

My object is to provide a method of quickly "aging" liquor—a method which is absolutely safe, and which is applicable under the existing laws.

In the accompanying drawing Fig. I is a diagrammatic view of a plurality of barrels organized with thermal apparatus in accordance with my invention, and in exemplary way is illustrative of how my method is conducted; Fig. II is a view to larger scale, showing the apparatus on the plane II—II of Fig. I; Fig. III is a view to still larger scale, showing, partly in side elevation and partly in vertical section, one of the thermal units of the apparatus employed; and Fig. IV is a fragmentary view, showing in vertical section the wall of a barrel and the body of liquor confined thereby.

In accordance with my method, I take the green liquor as it comes from the still, or as it is conditioned preparatory to bonding, and enclose it in the usual barrels, or other containers, in which the liquor normally is put in bonded storage. Such containers may be barrels 1 constructed of oak. As usual, the internal surfaces of the walls 2 of the barrels are charred, as indicated by the numeral 3 in Fig. IV. The green liquor is enclosed and sealed in the barrels 1, and the barrels are arranged, and conveniently are aligned, in close juxtaposition in the storage room (see Fig. I).

I organize a thermal device 4 with each barrel. Each thermal device 4 includes a cylindrical body 5 which is closed at its opposite ends by headers 6 and 7; within the body 5 a coil 8 of copper tubing is housed; the tubing at the upper end of the coil is projected through the header 6, and at its lower end the coil is projected through the header 7. A packing gland 9 seals the passage of the tubing through each header. Continuing upward from the header 6, the tubing comprises a conduit 10 which terminates in a pipe coupling 11 (Fig. II); while projecting from beneath the header 7, the tubing comprises a conduit 12, terminating in a pipe coupling 13.

The side wall of each barrel may be drilled, to receive two tap-valves 14 and 15, one tap-valve being located near the top of the barrel and the other near the bottom, as shown in Fig. II. The conduit 10 is secured to the upper tap-valve 14, by means of coupling 11, and conduit 12 is similarly secured to the lower tap-valve 15. Thus, it will be understood that the conduits 10 and 12, including between them the coil 8, comprise a by-pass between the top and bottom regions of the body of liquor stored in the barrel. It will be understood that a column of liquor is confined in the tubing 8, 10, 12, and that the body of liquor under treatment is sealed from the atmosphere.

I apply heat to the coil 8, and, in consequence of well-known thermo-syphonic action, liquor flows upward in the tubing. In consequence the body of liquor in the barrel is caused slowly to flow or circulate in the manner indicated by the arrows in Fig. II. The intensity of the heat applied to the coil is so determined that the temperature of the body of liquor is normally below 150 degrees F.; preferably, the temperature is maintained at about 120 degrees F., this apparently being the most effective temperature. Fig. IV illustrates the advantageous circulation of warm streams which the thermal or syphonic action effects in the body of liquor. A small contin-

uous stream of liquor is by-passed from the bottom of the barrel to the top, and heat is applied to such stream. The stream is drawn, relatively cool, from the bottom of the body of liquor, and 5 is returned at elevated temperature to the top of the body. The temperature differential between the top and the bottom of the body of liquor, together with the momentum of the slowly flowing, by-passed stream, effects a continuous movement 10 from the center of the body outward, whereby warm circulating streams flow from within the body of liquor into contact with the charred wall 3 of the barrel (see Fig. IV).

In the practical application of my invention 15 I organize a plurality of container units—the charred barrels 1 in this case—in alignment, and with each container unit I organize a thermal device 4 in the manner already described.

As has been already mentioned, the fire hazard 20 is great in heating alcoholic liquids. With this in mind, it will be perceived in the following description that the particular method I have developed for supplying heat to the group of thermal devices 4 is advantageous from the stand- 25 point of safety. Returning to Fig. III, it will be observed that cylinder 5 and headers 6, 7 define a closed or sealed housing for the coil 8. The header 7 is provided with an inlet passage 16, controlled by a valve 17, and the header 6 30 includes an outlet passage 18. Suitably heated liquid at from 120 to 150 degrees F. is introduced through valve 17, caused to flow upward through and around the coil 8, and then discharged by way of outlet 18. Advantageously, 35 hot oil is supplied to and circulated through the housing 5, 6, 7, to heat the coil 8. The heated oil (or other liquid) has a boiling point above the temperature to which the liquor is heated; that is, the oil has a boiling point of 40 at least 150 degrees F.

As indicated diagrammatically in Fig. I, I provide an inlet or feeding manifold 19 and an outlet manifold 20. The inlet valve 17 of each thermal device 4 is connected to the inlet manifold by means of a pipe 21, while, by means of a suitable pipe fitting (23), a pipe 22 connects the outlet passage 18 of each thermal device to the outlet manifold 20. I provide a boiler 24 for heating the oil, which may comprise a light 45 lubricating oil. The boiler is safely stationed at a point remote from the storage room in which the barrels 1 are located; the outlet of the boiler is connected by a pipe 25 to the inlet manifold 19, and a return pipe 26 connects the 50 outlet manifold 20 to the intake of the boiler. A pump 27 is organized to effect the flow of oil from the boiler to the inlet manifold 19. As indicated by the arrows in Fig. I, hot oil flows from the supply manifold 19 through each of 55 thermal devices 4, and is discharged into the return manifold 20, whence it flows, by way of pipe 26, back to the boiler 24 for reheating. Thus, a continuous stream of hot oil flows through each thermal device 4, and, without any fire hazard whatever, the coil 8 of each thermo-syphon 10, 12 is supplied with heat. It will be noted that the oil continuously flows in closed cycle from the boiler 24 and back again; the pump 27 manifestly may be a variable discharge 60 pump, whereby the rate of flow of the hot oil may be regulated to effect control of the tem-

perature to which the liquor is heated. The inlet valve 17 of each thermal device 4 affords independent regulation of flow through each device, and regulation of pump 27 admits of overall regulation of flow through the system. Thus, 5 the rate at which heat is supplied to the liquor of each unit container (each barrel 1 in this case) may be determined to a nicety, and optimum conditions may be maintained for the accelerated curing or quick "aging" of liquor. 10 Alternatively, or additionally, a thermostatic control mechanism may be included with the boiler 24. That is to say, the boiler may be a gas fired boiler, and, as the engineer will readily understand, a thermostatic mechanism (not 15 shown, but of well-known structure) may be organized to control the supply of fuel to the boiler, so that the temperature (to which the circulating oil or other liquid is heated) is automatically regulated. 20

When the barrel has once been used for the curing of liquor (certainly in the case of whisky), it is saturated with impurities, or is substantially or practically exhausted of the flavoring and coloring substances with which the liquor 25 must be supplied. In any case, the barrel does not serve with best results if it be used a second time, and the best practice has been to use a barrel only once.

It will be observed that the thermal devices 30 4 may readily and in a moment be attached to and detached from the barrels, whereby new barrels may be conveniently substituted for those which have been used. There is no difficulty in interchanging the barrels, and there is no incentive to depart from the recognized best practices of the art. 35

I claim as my invention:

1. In the "aging" of distilled alcoholic liquor, the herein described method, which includes enclosing the liquor in the presence of charred wood in a plurality of independent unit containers, by-passing a column of liquor externally of each container between two levels in the body of liquor contained therein, heating a liquid, having a boiling point of at least 150° F., at a point safely removed from said containers, distributing the heated liquid and maintaining circulating streams thereof severally in thermal communication with said by-passed columns of liquor, 45 and thereby raising the temperature of the confined bodies of liquor to approximately 120° F. and producing thermo-syphonic flow in the several bodies of liquor.

2. In the accelerated "aging" of distilled alcoholic liquor, the herein described method, which includes enclosing the liquor in a plurality of independent charred wooden barrels, heating a liquid, having a boiling point of at least 150° F., in a station safely removed from said containers 60 and conducting said liquid in heated condition to a supply manifold, by-passing streams of said heated liquid from said manifold severally into thermal communication with the bodies of liquid confined in said barrels, and, by thereby raising 65 the temperature of said bodies of liquor to approximately 120° F., maintaining thermo-syphonic flow or circulation in the several independent bodies of liquor.

WILBUR A. CARRELL. 70
